UNITED STATES PATENT OFFICE.

TONY ZABROCKI, OF WINONA, MINNESOTA.

PHOTOGRAPHIC-PRINTING APPARATUS.

1,116,195.

Specification of Letters Patent.

Patented Nov. 3, 1914.

Application filed July 11, 1913. Serial No. 778,436.

To all whom it may concern:

Be it known that I, TONY ZABROCKI, a citizen of the United States, residing at Winona, in the county of Winona and State 5 of Minnesota, have invented certain new and useful Improvements in Photographic-Printing Apparatus, of which the following is a specification.

This invention relates to photographic 10 printing apparatus, and more particularly to that class of photographic printers adapted to operate automatically.

The primary object of this invention is to 15 provide an automatic photographic printing apparatus adapted to use sunlight or an artificial light without a great change in the apparatus.

A further object of this invention is to 20 provide an automatic photographic printing apparatus adapted to be regulated with regard to the length of the exposure.

A still further object is to provide a printing apparatus adapted to register the number 25 of prints made thereby and to warn the operator when the desired number of prints is completed.

With these and other objects in view this invention consists in the peculiar combination and arrangement of the mechanism and 30 parts of an automatic photographic printing apparatus as hereinafter described and more particularly pointed out in the appended claims.

Referring to the drawings forming a part 35 of this specification wherein similar reference characters indicate similar parts whenever used, Figure 1 is a perspective view of the apparatus in a position to receive the necessary materials; Fig. 2 is a side elevation of the device in a printing position; Fig. 3 is a top plan view; Fig. 4 is a section through the device when printing by sunlight; Fig. 5 is a section through the device when printing by electricity. Fig. 6 is a detail 40 of the registry and alarm mechanism; Fig. 7 is a detail of the shifting ratchet of the registry mechanism; Fig. 8 is a detail of the alarm mechanism; Fig. 9 is a detail of the operating mechanism; Fig. 10 is a detail 45 of the operating mechanism; Fig. 11 is a detail of the operating mechanism and Fig. 12 is a detail of the operating mechanism, showing the valve controlling the piston rod.

50 14 designates a casing or box provided with a plurality of openings and provided

at one end with a vertical partition 15 forming a chamber 16 provided with a door 17. Upon the inner face of the door 17 are a plurality of clips 18 adapted to hold photographic plates or the like. An aperture 19 is formed in the rear of the casing 14, and is closed by a door 20. This aperture is for the purpose of permitting access to the interior of the device. Formed in the top of the casing is an aperture 21 which is closed by a glass plate 22. Hingedly connected to the top of the casing and adapted to cover the glass plate 22 is a door 23 composed of two sections 24, 25, hingedly connected at 26—26 by means of spring hinges which tend to force the forward section 24 upwardly, as shown in Fig. 1 and in dotted lines in Fig. 4. A stop 27 controls the upward movement of the section 25. The inner face of each of the sections 24—25 is covered by a thick felt pad 28. The door 23 is fastened to the casing 14, by means of a metal rod 30, passing through eyelets 31 upon the section 25, and thence through lugs 32 upon the casing when the end of the rod at 32' is bent downwardly through an aperture 33 into the chamber 16 when the rod 30 is provided with a hook 34.

Pivottally connected to the section 24 is a 85 latch member 35 guided by a keeper 36 and normally held in elevation by a spring 37. The latch member is provided with a bifurcated end 38 carrying a pin 39 adapted to engage a hooked member 40 located on the 90 interior wall of the casing. The member 40 is carried by a rod 41 which extends at right angles to the said member along the interior of the casing 14, being supported by bearings 42—42, and through the partition 95 15 into the chamber 16, where the rod is bent downwardly and inwardly and formed with a hook 43. This rod 41 is adapted to oscillate within the bearings 42 and is normally held against such movement by 100 means of a leaf spring 44 which forces said rod against the side of the casing. Any forward pull of the hook member 43 will cause a retrograde movement of the member 40, which will release the pin 39, releasing 105 the latch, which in turn releases the door 23, allowing the sections 24 and 25 to fly upwardly by the action of the spring 26.

The wall of the casing opposite the partition 15 is provided with an aperture which 110 is normally closed by means of a plurality of overlapping shutters 45, pivotally sup-

ported upon the side walls of the aperture. The movement of these shutters is controlled by means of a plate 46, which is connected thereto by means of crank levers 47, attached 5 to the pivots 45', and slots 48 controlling the crank levers which work therein. The sliding plate 46 is controlled by means of a pivoted lever 49, secured at 50 to the lower end thereof and pivoted at 51 to the interior 10 of the casing. The lever 49 is provided at its inner end with a notch 52, the purpose of which will be hereinafter explained. The return of the said lever 49 to normal is made certain by means of a leaf spring 52' operating 15 thereon.

In the bottom of the box, or in the side of the casing opposite the aperture 21, is placed an electric lamp socket 53 of the ordinary type and adapted to receive a lamp bulb 54. 20 Connected in a circuit with this socket is a knife-switch 55, which is normally held out of contact by means of a leaf spring 56 which forces the blade upwardly out of contact with the socket. The source of electricity 25 may be any suitable means connected to a wire 57. Attached to the blade of the knife switch 55 is a member 58 composed of fiber, or any other suitable insulating material, and provided in its lower portion with 30 a slot 59, the purpose of which will be hereinafter explained. The upward movement of the knife-switch 55 is suitably limited by means of a stop 60.

Slidably mounted in bearings 61 upon the 35 interior wall of the box is a vertical rod 62, provided with an inwardly projecting cam surface 63 and an upper bifurcated end 64 and upon its lower end with an outwardly extending pin 65. The bifurcated end 64 is 40 adapted to be engaged by the bifurcated end 38 of the latch-member 35, and to be pressed downward thereby when said latch-member is in locked position, as shown in Fig. 5. By means of a member 66 provided with 45 lugs 67 engaging the member 63, the said member may be shifted slightly from left to right, in order that the pin 65 may engage either the notch 52 of the lever 49, or the notch 59 of the member 58, accordingly as 50 to whether it is desired to print by means of natural or artificial light. The member 66 has a handle 68 extending through an aperture in the wall of the box, thus enabling the member 62 to be shifted when the box is 55 absolutely closed.

Acting upon the cam face 63 is a rod 69, extending through the door of the box and terminating in a handle 70, by means of which the member 62 may be raised and lowered independently of the latch mechanism.

When it is desired to print by means of natural light the member 62 is shifted until the pin 65 engages the notch 52, when any downward movement of the member 62 will 65 cause the lever 49 to tilt, which in turn op-

erates the member 46 and opens the shutter 45. Should it be desired to print by means of electric light the member 62 is shifted until the pin 65 engages the notch 59 of the member 58, whereupon any downward movement of the member 62 will actuate the knife-switch, to close the circuit and light the bulb 54. Arranged about the bulb 54 is an inverted pyramidal-shaped reflector 71, adapted to throw the light rays upward 75 against the glass plate, 22.

All the light controlling mechanism is covered by any suitable covering and an asbestos cover placed over the switch 55. The interior of the box is coated with any 80 suitable light reflecting medium and is made absolutely light-excluding with the exception of the glass plate 22 in the top thereof.

Secured to the wall of the partition 15 and lying within the chamber 16 is a vertical 85 guide way 72, provided at its upper end with a stop 73, carrying a pulley wheel 74. Slidably mounted in said guide way is a traveling plate 75 provided with anti-friction rollers 76 adapted to engage the guide way 90 72. Pivottally supported upon the member 75 is a dog 77, provided at its lower extremity with a hook portion 78 carrying anti-friction rollers 79. A chain 80 is secured to the top of the slide 75 and passes 95 over the pulley 74 and is secured to the hook 34 of the rod 30 in such a manner that when the door 23 is closed the chain will draw the slide to the top of the guide way.

Directly above the guide way 72 and secured to the top of the box is a plunger 81 which supports a cylinder 82 formed at its lower end with a heavy weight 83, or spring (not shown) so constructed as to draw the cylinder downward or against the pressure 105 of the air therein and the action of the plunger, said air pressure being controlled by means of a valve 84 located in an aperture in the top of the box, as shown in Fig. 12. Secured to the weight 83 is a chain 85, 110 passing over pulley wheel 86, and connecting with the hook portion 43 of the rod 41 in such a manner that the downward motion of the weight will cause the chain 85 to pull the hook member 43 forward to trip the 115 latch member 35, which releases the door 23 and by spring 27, automatically throws door 23 wide open.

The operation of the device is as follows: The film or plate and the sensitive paper are 120 placed in their proper relation upon the glass plate 22, the door 23 being open and thrown back to its open position as shown in Fig. 1. This opening of the door 23 has caused that portion of the rod 30 within the 125 chamber 16 to move forward, thus loosening the chain 80 and allowing the slide 75 to move by its own weight to the bottom of the track 72 where the pivoted member 77 moves outwardly upon the weight and al- 130

lows the hook member 78 to engage the under edge of the weight 83. The door 23 is now closed and latched, which causes the member 62 to be depressed to open the shutters or close the knife switch and the rod 30 to recede, raising the slide and the weighted cylinder upwardly on the track 72, to a point opposite the hook member 43, which strikes the upper end of the pivoted member 77 and kicks the same out from under the weight 83, as shown in dotted lines in Fig. 2. The weight because of gravity or spring (not shown) will travel downward upon the guide way 72 and the rod 81 until the chain 85 becomes taut, when a further downward pressure of the weight will cause the chain 85 to pull the hook member 43 of the rod 41 forward, which in turn moves the catch member 40 rearwardly, and releases the latch 35, whereupon the door 23 flies backward and the member 62 moves upwardly, allowing the shutters to close, or the knife-switch to resume its normal out of circuit position.

25 The pulley 86 is carried by a bifurcated arm 87, carried by a member 88, pivotally mounted at 89 on the partition 15, and carrying a telescoping member 90, extending upwardly through an aperture 91 in the top 30 of the box, where it is provided with a pawl 92, adapted to engage a rack 93, having a gage 94, divided to indicate any suitable periods of time. When the pawl 92 is set at a rack tooth opposite the gage mark of 35 a certain period of time the member 88 will be correspondingly moved about its pivot 89, thus moving the member 87, carrying the pulley 86 in such a manner as to regulate the slack of the chain 85 with regard to the 40 downward stroke of the weight 83, thus regulating the length of time that the device is in operative position.

Secured within the aperture 91 is a stationary rack 95 and a slidable rack 96. Movably-mounted between the racks 95, 96 is an indicator 97 formed with a pointer 98, adapted to travel along a scale 99, graduated to represent any suitable series of numbers as 0 to 50, etc. The member 97 is 45 formed of a stationary piece 99 provided with a groove 100, and a member 101 provided with a V-shaped jaw 102 at its outer end thereof, said member sliding in the groove 100. Secured to the under side of 50 the member 99 are spring rods 103 normally adapted to flare outwardly and engage the teeth of the rack bars 95, 96, but adapted upon a forward movement of the member, 55 sliding in the groove 100, to be engaged by the jaw 102 and forced inwardly and away from the rack teeth, thus permitting the member 97 to slide irrespective of the racks. The pointer 98 is set at any desired number along the scale to indicate the number of 60 prints required, and is then operated in the

following manner: The sliding rack 96 has formed upon it a lug 104, and is adapted to be normally pressed away from the wall of the box toward the valve 84, by means of a spring 105. The portion of the rod 30 70 extending downwardly into the clutch 16 engages the lug 104 in such a manner that when the section 25 of the door 23 is closed the rod will force the sliding rack backward, away from its normal position. Upon opening the door the rack will slide forward 75 under the action of the spring 105, and engage one of the pins 103. Upon the closing of the door the rod 30 strikes the lug 104, pulling the slide 96 backward, which causes 80 the rack to pull the member 97 with it a distance equal to one of the graduations upon the scale. This operation is continued until the member 97 is at a point opposite the zero mark upon the scale, when a lug 106 carried by the member 97 trips a hammer 107, which in turn strikes a bell 108, thus warning the operator that the required number of prints has been completed.

A spring held clamp 110 is provided for 90 holding the paper and the film or plate to be printed tightly against the glass 22.

Within the chamber 16 is provided a cleat 111, adapted to receive the coil of an electric wire when the same is not in use.

95 A hinged cover 112 is provided to cover the aperture 91 and the valve 84.

Below the opening 22 of the casing 14 is placed a suitable vignetting mechanism preferably constructed in the following manner: 100 Mounted upon depending partitions upon both sides of the opening 22 are plates 109—109 adapted to slide toward and away from the opening 22 by means of step by step slots f formed in the plates 109 and adapted 105 to be engaged by pins e e carried by the partitions. Formed in the upper portion of the sliding plates 109—109 are lugs b and b' adapted to receive a ground glass plate A. Upon this plate A is supported a paper mask 110 e provided with an aperture d, thus allowing of the exposure of only that part of the film or negative desired to be printed. By this construction it will be seen that the plates 109—109 may be easily moved toward or 115 away from the negative or film in order to get the correct amount of exposed surface, etc. Conveniently placed about the vignetting mechanism are a plurality of supplemental reflectors g, so placed as to direct the 120 light upwardly and to concentrate the light upon the ground glass plate A.

125 I am aware that considerable variation is possible in the details of construction herein shown and described, without departing from the spirit of my invention, and I do not intend to limit myself thereto, except as pointed out in the following claims, in which it is my intention to claim all the novelty inherent in the structure shown and 130

described as broadly as the state of the art will permit.

Having thus described my invention what I claim as new and desire to secure by Letters Patent is:

1. In an automatic printing device, the combination with a box, of means for controlling the supply of light to said box, means operatively placed in relation to said means, comprising a vertical sliding lever, a pinion on said lever, a cam face carried by said lever, and means for causing a relative shifting of the vertical lever.

2. In a printing device, a box provided with openings, a closure for one of said openings, a closure for another of the openings, mechanism for operating said last named closure, means carried by the first named closure adapted to operate the mechanism to operate the second mentioned closure, and means adapted to operate the second closure independently of the first mentioned closure.

3. In a printing device, a box provided with an opening, a closure for said opening, said closure comprising a plurality of pivoted plates, means for operatively connecting said pivoted plates, said means comprising a sliding member provided with a plurality of slots, crank arms upon the pivots of said plates, adapted to work in said slots, and means for operating said member to operate said plate.

4. In a printing device, a box provided with an opening, a closure for said opening, said closure comprising a plurality of pivoted plates, means for operatively connecting said pivoted plates, said means comprising a sliding member provided with a plurality of slots, crank arms upon the pivots of said plates, adapted to work in said slots, means for operating said member to operate said plates, said means comprising a pivoted lever mounted on said slideable member, said lever having a slot, and means adapted to engage such slot to operate the lever.

5. In a printing apparatus, a box formed with two apertures, means adapted to open and close one of said apertures, a closure for the other aperture, means within said box adapted to make and break an electric circuit, means operatively carried by said last mentioned closure adapted to operate the shutter or the circuit, and means for disconnecting the mechanism for opening and closing said first mentioned aperture and connecting the mechanism closing the circuit.

6. In a printing device, the combination with a box formed with a plurality of apertures, of a closure for one of said apertures, means for holding said closure in a closed position, said means comprising a latch member formed with an angular extension, a detent adapted to engage said angular ex-

tension, a member extending from said detent, a second extension carried by said detent, and a hook member carried by said second extension, and means for operating said detent to release the latch.

7. In a printing device, a box formed with an aperture, a closure for said aperture, a latch carried by said closure, a detent adapted to engage said latch, and means for operating the detent to release the latch, said means comprising a piston, a cylinder working over said piston and partially restrained thereby, and means between said cylinder and said detent whereby extreme downward movement of the cylinder will operate the detent to release the latch.

8. In a printing device, a box formed with an aperture, a closure for said aperture, a latch carried by said closure, a detent adapted to engage said latch, and means for operating the detent to release the latch, said means comprising a piston, a cylinder working over said piston and partially restrained thereby, means between said cylinder and said detent whereby extreme downward movement of the cylinder will operate the detent to release the latch, said means comprising flexible connections operatively connected thereto, and means for controlling the relative slack of said flexible connection to regulate the length of stroke of the cylinder.

9. In a printing device, a box formed with an aperture, a closure for said aperture, a latch carried by said closure, a detent adapted to engage said latch, and means for operating the detent to release the latch, said means comprising a piston, a cylinder working over said piston and partially restrained thereby, means between said cylinder and said detent whereby extreme downward movement of the cylinder will operate the detent to release the latch, said means comprising flexible connections operatively connected thereto, means for controlling the relative slack of said flexible connection to regulate the length of stroke of the cylinder, said means comprising a pivoted lever having a pulley engaging said connections, means for operating said pivoted lever, and means for determining the amount of movement necessary for said pivoted lever.

10. In a printing device, a box provided with an aperture, a closure for said aperture, a latch carried by said closure, a detent adapted to engage said latch, a cylinder, a piston for said cylinder, one of said members being attached to the box and the other movable in relation thereto, and means connecting the movable member to the detent, whereby the detent will release the latch when the movable member has moved a predetermined distance.

11. In a printing device, a box provided

with an aperture, a closure for said aperture, a latch carried by said closure, a detent adapted to engage said latch, a cylinder, a piston for said cylinder, one of said members being attached to the box and the other movable in relation thereto, means connecting the movable member to the detent, whereby the detent will release the latch when the movable member has moved a predetermined distance, and means to vary the distance to be traveled by the movable member.

12. In a printing device, a box provided with an aperture, a closure for said aperture, a latch carried by said closure, a detent adapted to engage said latch, a cylinder,

a piston for said cylinder, one of said members being attached to the box and the other movable in relation thereto, means connecting the movable member to the detent, whereby the detent will release the latch when the movable member has moved a predetermined distance, and means operated by the closure to engage the movable member to return it to its starting position.
